UNITED STATES PATENT OFFICE.

HORACE A. LOGAN AND FRANCIS R. WRIGHT, OF LATHROP, MISSOURI.

RUNNING-GEAR FOR VEHICLES.

SPECIFICATION forming part of Letters Patent No. 252,886, dated January 31, 1882.

Application filed November 23, 1881. (No model.)

To all whom it may concern:

Be it known that we, HORACE A. LOGAN and FRANCIS R. WRIGHT, citizens of the United States, residing at Lathrop, in the county of Clinton and State of Missouri, have invented certain new and useful Improvements in Running-Gears for Wagons; and we do hereby declare that the following is a full, clear, and exact description of the same, reference being had to the annexed drawings, making a part of this specification, and to the letters and figures of reference marked thereon.

Figure 1 of the drawings is an under side plan view of our invention; Fig. 2, an end view thereof, and Fig. 3 a sectional elevation taken on line *x x* of Fig. 2.

The present invention has relation to certain new and valuable improvements in the running-gear for wagons or other vehicles; and it consists in the details of construction, as shown in the drawings and hereinafter described.

In the accompanying drawings, A represents a wagon-body, to which is connected the usual frame, B, having the fifth-wheel C suitably fastened to the upper side.

To the under side of the body A is bolted or otherwise connected a rod, D, said rod having forked ends *a*, which are flattened to enable them to be firmly secured to the wagon-body. Other means, however, may be employed for attaching the rod D, which lies horizontally or parallel with the body A. The frame B passes over the end of a king-bolt, *b*, and is held thereon by a screw-nut, *c*, engaging with the screw-threaded end of said bolt, the frame moving horizontally in either direction to the right or left. The king-bolt *b* is formed at its upper end with a bifurcated head, *d*, which embraces a lug, *e*, depending from the under side of the wagon-body A. The forward end of the rod D is supported by a yoke, *f*, bolted or otherwise secured to the under side of the wagon-body, said rod extending beyond the yoke and passing through an eye or loop, *g*, projecting from a segmental bearing-plate, E. This bearing-plate E is formed with guides *h*, which embrace the outer edge or rim of the fifth-wheel

C. Thus the fifth-wheel is guided in its lateral or sidewise movement. The front end of the rod D is screw-threaded to receive a screw-threaded nut, *i*, to retain the eye *g*, with its bearing-plate, on the rod.

If preferred, the lug *e* may be formed with a screw-threaded bolt and attached to the under side of the body A by the bolt passing up through the same and held by a suitable screw-nut.

The peculiar construction of the inner end of the rod D, that is forked or bifurcated and flattened, admits of the rod being securely and firmly attached to the wagon-body, possessing great strength and durability, and resists the strain naturally produced by the oscillating or tilting motion of the wagon-body from side to side.

A wagon-gear constructed in accordance with our invention possesses superior strength, is much easier to ride than the wagons of ordinary construction, and less liable to get out of order.

Having now fully described our invention, what we claim as new, and desire to secure by Letters Patent, is—

1. In a wagon-gear, the body A, having connected thereto the horizontal rod D and lug *e*, in combination with the king-bolt *b*, fifth-wheel D, and segmental bearing-plate E, substantially as and for the purpose set forth.

2. In a wagon-gear, the body A, having connected thereto the rod D, yoke *f*, and lug *e*, and the bearing-plate E, having eye *g*, through which the rod passes, in combination with the frame B, fifth-wheel C, and king-bolt *b*, having head *d*, all constructed and arranged to operate substantially as and for the purpose specified.

In testimony that we claim the above we have hereunto subscribed our names in the presence of two witnesses.

HORACE A. LOGAN.
FRANCIS R. WRIGHT.
